[57] **CLAIM**

The ornamental design for a building for lubricating and oil servicing of automotive vehicles, as shown.

DESCRIPTION

FIG. 1 is a perspective view of the front and one end of the building;

FIG. 2 is an elevational view of the front of said building, on line 2—2 of FIG. 1;

FIG. 3 is an elevational view of one end of the building on line 3—3 of FIG. 2;

FIG. 4 is an elevational view of the rear of the building;

FIG. 5 is an elevational view of the other end of the building, on line 5—5 of FIG. 2.

FIG. 6 is a top plan view thereof.
